SOUND RECORDING

William E. Beatty, Hollywood, Calif., assignor to
 United Research Corporation, Long Island
 City, N. Y., a corporation of Delaware

Application July 24, 1935, Serial No. 32,855

11 Claims. (Cl. 179—100.3)

This invention relates to photographic sound recording apparatus and particularly to apparatus for reducing ground noise caused by the transparent portion of the sound track.

5 As is well known, most of the ground noise heard when a sound record of either variable area or variable density type is reproduced is the result of light passing through the apparently clear or transparent portion of the sound track which 10 contains scratches, particles of dust, enlarged grain, etc. What is desired, therefore, is that the sound track portions be opaque to light at the periods of no sound and only that portion thereof be transparent which is occupied by the 15 modulations.

In the art of variable area recording, it is customary to define a constant intensity beam of light by an aperture of a particular shape having at least one straight edge, and then to vary by a 20 moving mirror or similar means the position of the beam across a rectangular slit in accordance with sound waves. The slit is imaged upon the sound track portion of a moving film, the varying widths of opaque portions varying with the 25 amplitude of the sound waves. Ordinarily at times of no signal half of the light slit is illuminated thus forming equal width longitudinal strips of opaque and transparent regions constituting the sound track portion, the transparent 30 regions thereof introducing the noise. Although the proportion of opaque to transparent regions is substantially maintained at all volume levels, the noise produced at periods of low levels or at 35 times of no sound is so large that it is detrimental to high quality reproduction.

Heretofore sound recording systems of the variable area type have been equipped to reduce the ground noise by reducing the transparent portion of the track at low volume levels and 40 eliminating it entirely at times of no sound. This has been accomplished by employing a shutter or shutters which obscure the light up to the boundary of the sound record or by means 45 for biasing the mirror to vary the center line of the modulations.

When biasing of the oscillating mirror is employed, the zero or center of modulation is generally moved as close as possible to one edge of the transparent portion of the film so that all the 50 peaks of both the high and low volume level sounds are as close as possible to the edge of the sound track. Due to the shrinkage of the film or inaccuracies in the film guiding mechanism of the reproducing apparatus, the film has a tendency to weave sideways when passing the point of

sound translation; this weave being sufficient at times to allow one end of the light slit to cut off some of the wave peaks. Although the peaks of the high level sounds may be cut off a substantial amount without any apparent distortion of the reproduced sound, this is not true of the low level peaks.

One object of the present invention is to reduce ground noise in the record while keeping the zero line of modulation always in the center of the 10 sound track, and without using either the shutter or biasing arrangement above described.

This is accomplished by moving the light slit itself along a line substantially parallel to its length and in accordance with the volume of 15 sound being recorded. The slit itself allows only the necessary portion of the sound track to receive light, or in other words, produces a slit 20 effective for the particular volume level being recorded.

More particularly describing the invention, reference may be had to the accompanying drawings wherein

Fig. 1 is a diagrammatic circuit and optical arrangement for recording a variable area noise- 25 less reduction type of sound track.

Fig. 2 is a sectional view of a preferred form of slit mechanism and is taken along the line 2—2 of Fig. 3.

Fig. 3 is a transverse sectional view taken along 30 the line 3—3 of Fig. 2 with parts broken away.

Fig. 4 is an enlarged fragmentary view of a positive film having a sound track thereon, the negative of which has been produced by the arrangement shown in Fig. 1.

Fig. 5 is an enlarged fragmentary view of the slit member.

Fig. 6 is a diagrammatic circuit and optical arrangement showing a modified form of noise 40 reduction circuit.

Fig. 7 is an enlarged fragmentary view of a positive sound track the negative of which has been made by the circuit shown in Fig. 6; and

Fig. 8 is a diagrammatic view of a modified form of slit device.

Referring to Fig. 1, sound waves directed into the microphone 1 are recorded upon a moving light sensitive film 2. In circuit with the microphone 1 is a speech amplifier 3 and transformer 4. A galvanometer 5 having an oscillating mirror 6 is connected across the secondary of the transformer 4. A constant intensity lamp 7 projects a beam of light onto the mirror 6 through a condenser lens 8; a second lens 9, and a mask 10. An edge 11 of an aperture in the mask 10

forms a sharply defined edge on the beam of light projected on the mirror, this edge of light serving to form an edge on the sound track which represents the sound waves. The beam of light as it is reflected by the mirror 6 passes through a slit device 12, through a pair of objective lenses 13 and onto the film 2. Shunted across the output of the speech amplifier 3 is a noise reduction circuit 14 which passes a portion of the 10 audio current through an amplifier 15 and rectifier 16 from which it is passed into the slit mechanism 12 as will be hereinafter described.

Referring now to Figs. 2 and 3, I will now describe the preferred form of slit mechanism. The 15 hollow pole piece 18 is mounted as by screws 19 upon the face of a metallic base plate 20. Pole piece 18 has a rectangular opening therethrough as shown by the dotted lines 21 of Fig. 2. A magnetic frame 22 is mounted upon the plate 20 and has a hollow core 23 therein which forms a 20 pole piece adjacent the pole piece 18. An electromagnetic coil 24 is provided around the core 23 and is fed with direct current so as to produce a constant magnetic flux across the pole piece 25 18 and the pole piece provided by the core 23. A pair of insulated bridges 25 and 26 is mounted 30 on the base plate 20 at either side of the pole piece 18. A pair of current carrying vibratory ribbons 27 and 28 is laid across the bridges 25 and 26 and is clamped thereto by clamping pieces 29 and 30. The ends of the ribbons 27 and 28 are secured upon winches 31, 32, 33 and 34 which are adapted to vary the tension upon the ribbons 27 and 28. Electric conductors 35 30 and 36 connect the ends of the ribbons 27 and 28 in parallel across the output of the rectifier 16 (Fig. 1). A slit member 37 is cemented across the ribbons 27 and 28 directly in line with the hollow core 23 and the hollow pole piece 18.

Referring to Fig. 5, the ribbons 27, 28 are so 40 adjusted that when little or no current is flowing through both the conductors 27 and 28, the left hand edge of the slit 39, formed in the slit member 37, lies closely adjacent the edge 40 of the light beam 41, the edge 40 being produced by edge 11 of the aperture in the mask 10. It will be understood that the left edge 43 of the slit 39 is adapted to be moved in accordance with the envelope of the sound waves being recorded, while the edge 40 of the light beam 41 traverses the slit 39 in accordance with the volume and amplitude of the sound being recorded. When sounds of low volume are directed into the microphone 1 (Fig. 1) the oscillations of the galvanometer mirror 6 will be correspondingly small to produce a wave form of relatively small height, as shown at "S" (Fig. 4). A correspondingly low current will be by-passed through the circuit 14 where it is rectified and applied across the ends of the 50 ribbons 27 and 28, which are so adjusted that the slit member 37 lies in the position shown by the full lines of Fig. 5 when no or little current is applied. Adjustment of each of the ribbons 27 and 28 is accomplished through adjusting fingers 55 44 and 45 mounted on insulated blocks 46 and 47 provided on the upper surface of the base plate 20. The fingers 44 and 45 are attached by screws 48 at one of the ends thereof and have adjusting set screws 49 contacting the forward ends thereof whereby each of the ribbons 27 and 28 may be transversely adjusted.

When sounds of high volume are recorded in the microphone 1 (Fig. 1) an increase in current will be sent through the galvanometer 5 as 75 well as through the amplifier and rectifier com-

bination 15 and 16. Thus the size of the wave forms will be increased as shown at "L" (Fig. 4) and at the same time the increase in current through the ribbons 27 and 28 will produce a greater interaction between both of the ribbons 5 and the magnetic flux flowing between the hollow core 23 and the pole piece 18 to move the slit member 37 toward the position shown by the dotted lines 50 (Fig. 5). As the edge 43 of the slit 39 moves to the left, the curved boundary 51 of the film 52 (Fig. 4) will correspondingly move to the left as at 53 to accommodate the high level wave representations. This variation of the slit member 37 is directly proportional to the envelope of the sound waves being recorded until the mirror 6 reaches the maximum limit of its excursions at which time the slit member 37 will be moved into the dotted line position 50 shown in Fig. 5. At this point the distance between the edge 43 (in this position) and the edge 40 of the light beam 41 (at zero position) will equal one-half the amplitude of the wave form.

Fig. 7 shows a positive film having a sound envelope line 55, the corresponding line in the negative of which is formed by the movable slit device 56 of Fig. 6. The circuit shown in Fig. 6 is the same as that shown in Fig. 1 with the exception of the noise reduction portion. Instead of passing the envelope current from the noise reduction rectifier 16 directly to the current carrying ribbons 27' and 28', the current is passed first through an electro-magnet 57. A hinged contact 58 is normally held out of engagement with the magnet 57. A second contact 59 is provided in the ribbon circuit 60. When sound waves above a certain predetermined limit are recorded, the increase of current through the electro-magnet 57 will cause the contact 58 to swing into engagement with the contact 59 thus closing the ribbon circuit 60. A battery 61 or other suitable source of power is provided within the circuit 60 to throw the slit member 37' to the left to allow for higher level sound representations. Thus, the line 55 (Fig. 7) will have two positions, i. e. 62 for low level sounds and 63 for high level sounds.

Fig. 8 shows a modification in which the slit member 65 is formed adjacent the outer edge of a vibratory reed member 66. Reed 66 is secured to a stationary member as at 67. When sound is directed into the microphone 68, a portion of the audio frequency current thus generated is directed into the circuit 69 to the galvanometer, not shown. The other portion of the audio current being directed through a noise reduction circuit 70 including a rectifier and amplifier combination 71 and 72, from whence it is passed through a coil 73 formed on the reed 66. Current sent through the coil 73 will produce a magnetic flux within the body of the metallic reed 66. The interaction between the magnetic flux produced by the coil 73 and the flux produced by the electro-magnets 74 will cause the reed 66 to move to the left in accordance with the volume of the sound being recorded. Thus, when high level sounds are being recorded, the member 66 will be moved into the dotted line position 75 to allow maximum excursions of the galvanometer mirror to project a light beam through the slit 65 and onto the film. A pair of stops 77 and 78 is provided to limit the movement of the reed 66 in either direction. Suitable damping means such as an air vane 79 on the reed 66 may be provided. It is to be understood that the invention, when operating on the rectified or envelope current for

variable area records, may be used in conjunction with any type of light beam modulating device.

What is claimed is:

5. 1. An apparatus for photographically recording sound on a moving film comprising, in combination, a member having an aperture, means for directing a modulated beam of light through said aperture, means for moving said member transversely of the film in accordance with the volume level of the sound to be recorded, and means for focusing an image of said aperture on the film. 10
15. 2. An apparatus for photographically recording sound upon a moving light sensitive film comprising, in combination, a member having a rectilinear slit therein, means for directing a modulated beam of light through said slit, means for moving said member in accordance with the volume level of the sound waves to be recorded, and means for focusing an image of said slit on the film. 20
25. 3. An apparatus for recording anti-ground noise type of sound records comprising, in combination, a member having an aperture therein, means for modulating a light beam across said aperture in accordance with sound waves to be recorded, means for moving said aperture member in accordance with the envelope of said sound waves, and means for focusing an image of said aperture on the film. 30
35. 4. In a device for recording anti-ground noise type of variable area sound records, the combination of a member having a rectilinear slit therein, means for directing a beam of light through said slit, means for modulating said beam of light in accordance with sound waves to be recorded, means for moving said member in accordance with the envelope of said sound waves, and means for focusing an image of said slit on the film. 40
45. 5. In a device according to claim 4 wherein said member is moved substantially parallel to the length of said slit. 50
55. 6. An apparatus for recording anti-ground noise type of variable area sound film records which comprises the combination of means providing a beam of light, means for varying the width of said beam in accordance with the wave form of sound waves to be recorded, a member having a rectilinear slit therein placed in the path of said modulated light beam, means for moving said member substantially parallel to the length of said slit and in accordance with the envelope of said sound waves, and means for focusing said slit on the film. 55
7. An apparatus for recording sound on a photographic film comprising a magnet, a vibratile electrical conductor in the field of said magnet, an opaque member secured to said conductor and having a light transmitting portion thereon, means for moving said conductor in accordance with the amplitude of sound to be recorded, means for directing a modulated beam of light on said opaque member, said beam being modulated in accordance with sound being recorded, and means for focusing said light transmitting portion of said member on said film. 10
8. A vibratile electrical conductor adapted to be moved in accordance with sound waves, said conductor having a rectilinear slit movable therewith, means for moving said slit in accordance with the volume of said sound waves, a light sensitive surface, and means for focusing said slit on said surface. 15
9. In a sound recording apparatus, the combination of a frame, a pair of vibratile electrical conductors secured to said frame, means for impressing on said conductors electrical currents corresponding to the amplitude of sound to be recorded, an opaque member secured to said conductors intermediate their ends, said member having a rectilinear light transmitting slit therein, means for modulating the light transmitted by said slit in accordance with said sound, a light sensitive surface, and means for focusing said slit on said surface. 20
10. In a sound recording apparatus, the combination of means providing a magnetic field, a pair of substantially parallel vibratile electrical conductors in said magnetic field, means for impressing on said conductors electrical currents corresponding to the amplitude of sound to be recorded, an opaque member secured to said conductors, said member having a rectilinear light transmitting slit therein substantially perpendicular to said conductors, means for modulating the light transmitted by said slit in accordance with said sound, a light sensitive surface, and means for focusing said slit on said surface. 30
11. The method of photographically recording sound upon a light sensitive record which comprises modulating a beam of light in accordance with sound waves, directing said modulated beam of light upon a narrow slit extending across the direction of movement of said record to record said sound waves, focusing said slit upon said record, and moving said slit parallel to the length thereof during said recording in accordance with the volume of said sound waves, whereby the exposure of the unmodulated portion of the sound track is substantially prevented. 40
